(57) **CLAIM**

The ornamental design for a cigar and lighter holder, as shown and described.

DESCRIPTION

FIG. 1 is a perspective view of a cigar and lighter holder illustrating our new design;

FIG. 2 is a left side view thereof, with the right side view being a mirror image thereof;

FIG. 3 is a rear view thereof;

FIG. 4 is a front view thereof;

FIG. 5 is a top view thereof; and,

FIG. 6 is a bottom view thereof.

The broken lines, immediately adjacent the solid line disclosure, represent the bounds of the claim and all other broken lines are for illustrative purposes only. None of the broken lines form a part of the claimed design.
